His Attorney.

UNITED STATES PATENT OFFICE.

ALVIN D. KEENE, OF SCHENECTADY, NEW YORK, ASSIGNOR TO GENERAL ELECTRIC COMPANY, A CORPORATION OF NEW YORK.

ELECTRIC WELDING SYSTEM.

1,246,106.

Specification of Letters Patent. Patented Nov. 13, 1917.

Application filed May 1, 1916. Serial No. 94,628.

To all whom it may concern:

Be it known that I, ALVIN D. KEENE, a citizen of the United States, residing at Schenectady, in the county of Schenectady, State of New York, have invented certain new and useful Improvements in Electric Welding Systems, of which the following is a specification.

My invention relates to welding systems, particularly to electric arc welding systems. One object of my invention is to provide a system in which the overload protective device operates at substantially a constant per cent overload although, if desired, the character of the load itself may be changed with a consequent change of normal load current.

To this end the overload protective device is controlled by an increase of voltage drop across the regulating rheostat. Preferably a controlling solenoid thereof is connected across that rheostat. Other necessary or desirable resistances may be included in the system. Particularly to take care of abrupt and substantial changes in the resistance at the work, as by the substitution of metal for carbon electrodes or vice versa in arc welding systems, I provide means for increasing and decreasing the effect of the voltage drop on the protective device as by providing a resistance member which may be included in circuit with the controlling solenoid as the occasion requires.

My invention will be better understood from the following description of the embodiment of it in the arc welding system diagrammatically illustrated in the single figure of the accompanying drawing.

The generator 1 which is compound wound is the source of electrical energy. The arc is drawn between the electrode 2 and the work 3 and constitutes the load, the electrode and work being respectively connected to opposite sides of the generator and the work constituting one of the electrodes. An automatically operated circuit breaker 4 may be used between the generator and the load at 2 and 3 to open the circuit on such overloads on the generator as do not affect the protective device later described. Between the load and the source is the rheostat 5 for regulating the amount of current supplied to load. A resistance 6 may be used in addition to limit the amount of current which can be supplied to the load with the rheo-

stat operating on its lowest point of resistance. The rheostat is somewhat peculiarly constructed, its movable arm or contact 7 being arranged to run over a circular contact, one portion 8 of which is conducting, the other portion 9 being insulated. The protective device or means comprises the contactor 12, the circuit of the solenoid 14 of which is opened and closed by the relay 13. The solenoid 15 of the relay 13 controls the operation of the protective device and is connected across the rheostat 5 so as to be acted upon by a voltage proportional to the potential difference across that rheostat at each instant; one side of the solenoid 15 is connected to the system at 16 on the generator side of the contactor 12 and on the other side is provided with two connections to the rheostat arm 7, one connection 20 being made to the conducting portion 8 of the circular contact on the rheostat, the other connection 21 being made through a resistance 22 direct to the arm of the rheostat. When the solenoid 15 raises its armature, it opens the circuit through the solenoid 14 and thereupon the contactor 12 opens the welding circuit. Since the solenoid 14 is connected across the generator 1 as shown the contactor 12 closes the welding circuit so long as the relay 13 is closed irrespective of whether the circuit is completed at the load. With the rheostat arm 7 in engagement with the portion 8 of the rheostat circular contact, the resistance 22 is in effect out of the circuit through the solenoid 15, being short-circuited by the connection 20. A manually operated switch 23 is provided for short-circuiting the resistance 22 when desired as hereinafter indicated.

The rheostat circular contact is so related to the rheostat arm that when that arm 7 is in engagement with any of the low resistance points of the rheostat usually used for working with a carbon electrode, it is also in engagement with the conducting portion 8 of the circular contact; correspondingly when the rheostat arm 7 is in engagement with the higher resistance points of the rheostat usually used when working with a metal electrode, the arm 7 is in engagement with the insulated portion 9 of the circular contact. As will be understood later, the insulated portion 9 of the circular contact may be omitted so far as the operation of my invention is concerned but for mechani-

cal reasons it is sometimes desirable to employ this insulated portion 9 rather than omit this portion altogether.

The solenoid 15 is designed to raise its armature and open the welding circuit on some predetermined percent increase in the potential difference across the rheostat, and hence coincident with some certain percent overload or increase in current supplied to the load. If this operation is arranged for with carbon for example as the electrode 2, and with the arm 7 on some point of the rheostat, the solenoid 15 will continue to raise its armature at about the same percent overload when the arm 7 is moved to other points of the rheostat throughout a fair range although the current supplied to the carbon arc is varied materially by such movement. If the system were to be employed with but one type of load, as a carbon electrode and arc exclusively, the resistance 22 and insulated portion 9 of the circular contact might be altogether omitted and the solenoid 15 connected directly to the rheostat arm 7. If, however, a substantial change is made in the resistance at the load as when a metallic electrode is substituted for the carbon electrode, the armature of the solenoid 15 is raised at a materially different percent of overload due to this difference in resistances, and hence to the difference between the parts of the total voltage consumed in the rheostat in the two cases unless some arrangement is made to counteract this effect. The resistance of an arc drawn to a metal electrode is considerably less, relatively speaking, than the resistance of an arc drawn to a carbon electrode. Due to this difference in resistances the rheostat is usually operated on higher resistance points when metallic electrodes are used as hereinbefore indicated. In order that the same system may be used for either carbon or metallic electrodes, the resistance 22 is provided and is included in the circuit through the solenoid 15 when the rheostat is operated on the higher resistance points usually used for metallic electrodes. This resistance 22 decreases the effect of the voltage drop across the rheostat on the solenoid 15 to an extent corresponding to the increase in that voltage drop resulting from the substitution of a metallic electrode for the carbon electrode. After the substitution of the metallic electrode therefore, the protective device continues to operate at something like the original percent overload; in other words, the current supplied to the metallic arc may be changed in value by changing the setting of the rheostat as before without departing to an impractical extent from this percent overload for the operation of the protective device.

At times it may be desired to operate a carbon electrode at a lower current value

than is possible by the system so far described, for the resistance 22 (and the insulated portion 9 of the circular contact) limits the movement of the arm 7 with a carbon arc; after any movement of the arm 7 which includes the resistance 22 in the circuit through the solenoid 15, this solenoid operates (with a carbon electrode and arc) only at a considerable higher value of percent overload than is desired. To take care of this fairly unusual case, the manually operated switch 23 is provided. With this switch closed the carbon electrode may be used with unusually low value of current, the solenoid 15 picking up its armature at substantially the desired percent overload while the rheostat is operated over its full range.

While I have described the principle of my invention and the best mode I have contemplated for applying this principle, other modifications will occur to those skilled in this art and I aim in the appended claims to cover all modifications which do not involve a departure from the spirit and scope of my invention.

What I claim as new and desire to secure by Letters Patent of the United States, is:—

1. A welding system comprising a source of energy, means for connecting the same to a welding load, a rheostat in said connecting means, and a protective device responsive to a variation of voltage between the terminals of said rheostat.

2. An arc welding system comprising a source of energy, electrodes connected thereto, a rheostat between said electrodes and source, and means for reducing the supply of energy to the electrodes responsive to a predetermined increase of voltage drop across said rheostat.

3. A welding system comprising a source of energy, electrodes connected thereto, a rheostat controlling the supply of energy to said electrodes, and protective means controlled by an increase of potential difference across said rheostat above a predetermined value.

4. An arc welding system comprising a source of energy, electrodes connected thereto, a rheostat between said electrodes and source, means for reducing the supply of energy to said electrodes, and a solenoid controlling said means connected to the circuit at opposite sides of the rheostat.

5. A welding system comprising a source of energy, electrodes connected thereto, a rheostat between said electrodes and source, means for reducing the supply of energy to said electrodes, a solenoid controlling said means connected to the circuit at opposite sides of the rheostat, and means for increasing and decreasing the resistance in the connections between said solenoid and the circuit.

6. An arc welding system comprising a source of energy, electrodes connected thereto, a rheostat between said electrodes and source, means for reducing the supply of energy to said electrodes, a solenoid controlling said means connected to the welding circuit at opposite sides of the rheostat, a resistance, and means for inserting said resistance in circuit with said solenoid between 5 said solenoid and the welding circuit.
7. An arc welding system comprising a source of energy, electrodes connected thereto, a rheostat between said electrodes and source, means for reducing the supply of 10 energy to said electrodes, a solenoid controlling said means connected to the welding circuit at opposite sides of the rheostat, and means for increasing and decreasing the effect on the solenoid of the voltage across the 15 rheostat.
8. An arc welding system comprising a source of energy, electrodes connected thereto, a rheostat between said electrodes and source, means for reducing the supply of 20 energy to said electrodes responsive to an increase of potential difference across said rheostat, and means for increasing and decreasing the effect of such potential difference on the energy reducing means.
9. A welding system comprising a source of energy, welding electrodes connected thereto, a rheostat connected in series with 25 said electrodes, means for automatically reducing the supply of energy to said electrodes responsive to a predetermined increase of potential difference across said rheostat, a resistance having one terminal 30 connected to said reducing means and a connection for automatically placing said resistance in series with said rheostat when the setting of the rheostat exceeds a predetermined value.
10. A welding system comprising a source of energy, a welding circuit connected thereto, a series rheostat in said circuit having a 35 movable member in contact with a stationary conducting member over the lower range of the rheostat, a protective device comprising a contactor in series with said rheostat and a magnet operatively connected 40 to said contactor, a controlling magnet connected to operate said protective device, a connection between one terminal of said controlling magnet and a point intermediate said source, and said rheostat, a circuit connection between the opposite terminal of said controlling magnet and the stationary 45 conducting member of said rheostat, a second circuit connection between the last mentioned terminal of the controlling magnet and the movable member of the rheostat, and a resistance in said second connection.
- In witness whereof, I have hereunto set my hand this 29th day of April 1916.

ALVIN D. KEENE.
